UNITED STATES PATENT OFFICE.

GEORGE LAW, OF YORK, PENNSYLVANIA.

OPEN-HEARTH-FURNACE DOOR AND FRAME.

1,391,197.

Specification of Letters Patent. Patented Sept. 20, 1921.

Application filed July 15, 1920. Serial No. 396,395.

To all whom it may concern:

Be it known that I, GEORGE LAW, a citizen of the United States, residing at York, in the county of York and State of Pennsylvania, have invented certain new and useful Improvements in Open - Hearth - Furnace Doors and Frames; and I do declare the following to be a full, clear, and exact description of the invention, such as will enable others skilled in the art to which it appertains to make and use the same.

My invention relates to water-cooled frames and doors for furnaces, designed more particularly for use in connection with furnaces of the open hearth type, employed in metal smelting.

The principal objects of this invention are to provide an arched water-cooled frame formed of sections secured in the door opening of the furnace in a novel manner which renders them readily removable for repairs or renewing; to connect the sections of the arched frame in a manner to prevent flame from licking through the joints between them and between the frame and door; and to provide the vertical legs of the frame with rearwardly diverging inner sides, thereby allowing the usual metal supply bucket to swing from side to side for equally distributing metal in the furnace and permitting withdrawal of said bucket without catching on the legs, as now often occurs.

With the foregoing in view, the invention resides in the novel construction and combination of parts hereinafter described and claimed, the descriptive matter being supplemented by the accompanying drawings, forming a part of this specification.

Figure 1 is a front elevation of a portion of an open hearth metal furnace equipped with my improved door and door frame.

Fig. 2 is a top plan view of the door and door frame showing the furnace wall in horizontal section.

Fig. 3 is a horizontal sectional view taken on the plane indicated by line 3—3 of Fig. 1.

Fig. 4 is a vertical transverse section as indicated by the irregular line 4—4 of Fig. 1.

Fig. 5 is a vertical longitudinal section as designated by line 5—5 of Fig. 4.

Fig. 6 is a horizontal section on the plane of line 6—6 of Fig. 1.

Fig. 7 is a detail horizontal section through the lower end of the door.

In the drawings above briefly described,

the numeral 1 designates a portion of an open hearth metal furnace, said furnace having a rectangular door opening 2 whose lower side is provided with the usual or any preferred dead plate 3 which projects forwardly from the furnace wall as shown for instance in Figs. 2 and 4. Extending across the upper end of the opening 2 and supporting the portion of the wall above said opening, is a horizontal beam 4 which is preferably of the channeled type illustrated most clearly in Fig. 4, although it will be understood that said beam might be of other cross sectional shape if desired. This beam not only supports the portion of the wall 1 over the opening 2, but it serves as the principal anchoring means for the detachable water-cooled frame for the opening 2.

The door frame above mentioned, as illustrated most clearly in Figs. 4, 5 and 6, comprises two inverted L-shaped sections 5 which jointly form an arched door frame, the vertical sides or legs 6 of said frame being in contact with the vertical sides of the opening 2, while the horizontal reaches 7 of the two sections 5, which reaches form the crown of the arch, bear against the upper edge wall of the opening, the free ends of said reaches being in abutting relation with each other as shown in Figs. 2 and 6. These abutting ends are provided with an interfitting bead and groove 8 and 9 respectively, which not only hold said ends against relative inward and outward movement, but prevent flame from licking through the joint between the two sections. The parts 7 of the frame section 5 are secured together at their lower sides by means of bolts 10 passing through angle-irons 11 which are secured to said parts by welding or in any other suitable way, but the upper sides of these parts are by preference connected in a different manner, namely by bolting the upturned ends 12 of the longitudinal angle-irons 13 together, as indicated at 14. One flange of the angle-iron bars 13 is secured to the frame section by rivets, while the other flange is embedded in the wall 1 as shown clearly in Fig. 4, thereby serving as means for partially anchoring the upper ends of the frame sections.

The upper and lower halves of the back walls 15 of the reaches 7, are horizontally offset as shown most clearly in Fig. 4, thereby providing a horizontal ledge 16 and a vertical wall 17 rising therefrom, these parts

16 and 17 jointly forming a seat which snugly receives the beam 4 above described. Both sections 5 are bolted to this beam as shown at 18 in Fig. 4 and it will thus be seen that at their upper ends, said sections will be rigidly held in place, but may be readily detached whenever one or both of the frame sections should be removed for repairing or renewing. To secure the lower ends of the sections 5 in place, the legs 6 are provided with forwardly extending feet 19 which are secured by bolts 20 to the dead plate 3.

To permit the usual metal supply bucket (not shown) to be swung freely from side to side when it is inserted through the opening of the door frame, and to prevent catching of the bucket on the frame when withdrawing said bucket, I prefer to dispose the inner opposed sides of the two legs 6 in rearwardly diverging relation throughout their width as shown at 21 in Figs. 3 and 6. This construction is also of advantage in effecting pouring of the molten metal from the furnace. When the frame comes in contact with the molten metal, it would be greatly injured, were it not for the fact that the sections 5 are of hollow formation and are completely filled at all times with water. Cold water is supplied through pipes 22 leading to the lower ends of the legs 6 and as the water is heated within the frame, it is withdrawn through pipes 23 rising from the upper ends of said frame. Vents 24 rise from both sections of the frame to allow the escape of any steam which might be formed therein, and for the purpose of resisting any internal pressure which may be created, the front and back sides of the two frame sections are connected by appropriate stay-bolts 25.

In connection with the frame structure above described, I prefer to employ a vertically sliding hollow door 26 mounted at the outer side of the frame in suitable guides 27 and adapted to be raised and lowered by a chain 28 or any other adequate means. Cold water is fed to the bottom of the door 26 through appropriate water inlet pipes 29, the hot water is carried from said door through pipes 30, and vents 31 are employed to allow the escape of steam, since such steam is formed from the terrific heat, even though both the outer and inner sides of the door are preferably lined with fire clay, as indicated at 32.

Attention may here be directed to the fact that the door 26 fits rather tightly against the outer side of the door frame, the connecting means between the several sections of

said frame being such as to interfere in no manner with this contact, thus preventing the escape of any flame and gases between the door and frame. The interior of the furnace may be viewed whenever necessary through the peep-pipe 33 which is normally closed however by an appropriate damper 34. From time to time, when sediment collects in the hollow door and frame, such sediment may be withdrawn by removing the screw-plugs 35 and draining all water from the door and frame.

By constructing my invention in the novel manner shown and described, it will be highly efficient and in every way desirable, and I therefore prefer to employ the several details disclosed. Nevertheless, it is to be understood that within the scope of the invention as claimed, numerous minor changes may well be made.

I claim:

The combination with a metal furnace having a rectangular door opening; of an arched water-cooled door frame fitting snugly in said door opening, the crown of said frame having the upper and lower halves of its back wall offset horizontally, forming a horizontal ledge extending forwardly from the upper edge of said lower half and a vertical wall rising from the front edge of said ledge, said ledge and wall jointly providing a right-angular seat extending throughout the length of said crown, a rigid beam snugly received in said seat and anchored at its ends in the furnace wall, means rigidly securing said vertical wall to said beam to reinforce said crown; said crown being transversely divided at its central point into two sections, a pair of angle iron bars extending longitudinally along the upper edges of said sections and having their inner ends bent to form upstanding lugs disposed in contact with each other, means securing said lugs together, one flange of each angle iron bar being secured to said crown while the other flanges of said bars are embedded in the furnace wall, a pair of relatively short angle iron bars having horizontal flanges extending transversely of and secured to the lower edges of the aforesaid crown sections, said bars having vertical flanges in contact with each other, and means securing these vertical flanges together.

In testimony whereof I have hereunto set my hand.

GEORGE LAW.
